UNITED STATES PATENT OFFICE

132,844

DESIGN FOR AN ANGLE DRESSER FOR ABRADING ELEMENTS

Earl G. Goehle, Huntington Woods, Mich.
Application May 21, 1942, Serial No. 106,971

Term of patent 7 years

To all whom it may concern:

Be it known that I, Earl G. Goehle, a citizen of the United States, residing at Huntington Woods, in the county of Oakland and State of Michigan, have invented a new, original, and ornamental Design for an Angle Dresser for Abrading Elements, of which the following is a specification, reference being had to the accompanying drawing, forming a part thereof, in which:

Fig. 1 is a view in perspective of an angle dresser for abrading elements, showing my new design;

Fig. 2 is a front elevational view;

Fig. 3 is a side elevational view; and

Fig. 4 is a top plan view.

The dresser bar shown in dot and dash lines in Fig. 1 has been omitted in the other views for convenience of illustration.

The dominant features of the design reside in the portions shown in full lines.

The stippled shading throughout the several drawing figures represents painted surfaces contrasting with the remaining bright metal surfaces.

I claim:

The ornamental design for an angle dresser for abrading elements, substantially as shown and described.

EARL G. GOEHLE.
